[57] CLAIM

The ornamental design for a cable connector, as shown and described.

DESCRIPTION

FIG. 1 is a perspective view of a male portion of a cable connector showing my new design.

FIG. 2 is a perspective view of a female portion of a cable connector showing my new design.

FIG. 3 is a right end view of the male portion of a cable connector as shown in FIG. 1 showing my new design.

FIG. 4 is a side view of a male portion of a cable connector showing my new design.

FIG. 5 is a side view of a male portion cable connector showing my new design.

FIG. 6 is a left end view of the male portion of a cable connector as shown in FIG. 1 showing my new design.

FIG. 7 is a top view of a male portion of a cable connector showing my new design.

FIG. 8 is a bottom view of a male portion of a cable connector showing my new design.

FIG. 9 is a left end view of the female portion of a cable connector as shown in FIG. 2 showing my new design.

FIG. 10 is a side view of a female portion of a cable connector showing my new design.

FIG. 11 is a side view of a female portion of a cable connector showing my new design.

FIG. 12 is a right end view of the female portion of a cable connector as shown in FIG. 2 showing my new design.

FIG. 13 is a top view of a female portion of a cable connector showing my new design.

FIG. 14 is a bottom view of a female portion of a cable connector showing my new design; and,

FIG. 15 is a perspective view of a connected male portion and female portion of a cable connector showing my new design.

The connector referenced in the claim is the combined male and female portions. The male and female portions are shown separately for the purpose of a complete disclosure.
